ATTORNEY.

UNITED STATES PATENT OFFICE.

LEE A. YEAGER, OF AKRON, OHIO.

WINDOW SCREEN.

Application filed March 4, 1920. Serial No. 363,318.

To all whom it may concern:

Be it known that I, LEE A. YEAGER, a citizen of the United States, residing at Akron, in the county of Summit and State 5 of Ohio, have invented new and useful Improvements in Window Screens, of which the following is a specification.

This invention relates to window screens and one of the objects thereof is to provide 10 a screen which will freely admit light and air and which will be strong and durable, serve to protect the window from breakage or unauthorized intrusion and prevent insects from entering therethrough.

Another object is to provide a window 15 screen having an outer panel of strong wire netting of coarse heavy open meshed wire fabric and an inner panel of wire gauze or fine open woven wire fabric.

A still further object which may be considered in connection with the above objects, is to provide a screen in which the 20 said panel of thin wire fabric may be removed during the season of the year when it is unnecessary to protect the opening against the entrance of insects, without disturbing the protective heavy wire panel.

Screens are ordinarily used to keep out 25 flies, mosquitoes and other insects; protecting the window against breakage or for protection against intrusion.

It is well known that a screen which will prevent the entrance of insects must be of a fine wire fabric which is easily torn or 30 broken. It is also well known that a screen which will effectually protect a window against breakage or which will tend to keep out intruders must be of strong heavy wire fabric of very large mesh.

It is apparent that to properly protect 35 a window, both the heavy wire cloth and the fine wire cloth must be used. It is therefore a purpose of this invention to provide a compact, easily cleaned window 40 screen having both a strong, coarse, open meshed wire fabric panel and a relatively fine wire gauze panel.

The above objects are attained and the 45 above objections are overcome by the novel construction, arrangement and combination of parts hereinafter described and illustrated in the accompanying drawings, wherein I have shown an embodiment of the invention, it being understood that the 50 invention is capable of various adaptations

and that changes and variations may be resorted to which come within the spirit of the invention or the scope of the claims hereunto appended.

In the drawings in which similar numerals of reference are employed to designate corresponding parts, throughout the several views,

Figure 1 is a cross sectional view of an 55 adaptation of my invention taken approximately on line 1 of Figure 2, and showing the same operatively positioned in a window frame.

Figure 2 is a plan view of the inner 60 side of same taken approximately on line 2 of Figure 1, and having portions broken away to more clearly illustrate the invention.

Referring now to the drawings in detail, the numeral 3 is used to denote a window 65 frame, and the numeral 4 a window sash. The numeral 5 denotes a screen frame which is adapted to fit into the window frame 3.

The numeral 6 denotes a layer of heavy 70 wire netting, strong, open meshed wire cloth or other reticulated material which is secured to the outer surface of the screen frame 5 so as to entirely cover the opening 75 therein. The numeral 7 indicates a half round molding or batten which is secured over the wire cloth 6, with its inwardly extending edge approximately in line with the inner extending edge of the frame 5. The

numeral 8 indicates a screen frame adapted 80 to exactly fit into the opening in the frame 5 so that the outer face thereof will be in contact with the layer of heavy wire fabric 85 6, and the inner face of the frame 8 will lie in the same plane as the inner face of the frame 5. Attached to the inner face of the frame 8 is a layer of wire gauze or relatively fine open meshed wire cloth which is positioned 90 thereon so as to completely cover the opening therein. The half round molding 10 is similar to the molding 7 and is attached to the frame 8 over the outwardly extending 95 edges of the wire cloth 9. The inwardly extending edge of the molding 10 being in line with the inwardly extending edge of the frame 8. The numeral 11 is used to indicate a turn button which is used to secure 100 the frame 8 in position on the frame 5. The numeral 12 denotes an eye screw which is driven into the inner face of the frame 5 and the numeral 13, a hook loosely secured 105 in said eye 12. The numeral 14 indicates 110

an eye screw fixed to the frame 3 into which the hook 13 is adapted to be entered to secure the screen frame 5 in the frame 3.

In use, the frame 5 is positioned inside the 5 window frame 3 at a point adjacent its outer edge and is secured thereto by the fastening means 12, 13 and 14 above described. The 10 screen 8 is then positioned within the screen frame 5 as shown in Figure 2 and the but- 15 tons, 11 are turned to hold the same in position.

During the winter months, when no pre- 15 caution need be taken to prevent the entrance of insects, the frame 8 may be re- 20 moved and stored in a dry place without disturbing or in any way interfering with the frame 5 and the frame 8 may be quickly and easily replaced when desired.

It is to be understood that the frame 5 20 may be secured in the frame 3 by any con- 25 venient fastening means and that the frame 8 may be secured in the frame 5 by means other than the buttons 11.

It will thus be seen that I have provided 25 a strong, compact, convenient device which will accomplish all of the objects above set forth and which constitutes an important advancement in window screen construction.

Having thus described my invention what I claim as new and desire to secure by 30 Letters-Patent is:—

1. In a device of the class described, in combination, a window frame, a frame detachably secured therein, the outer side of said last mentioned frame covered with open 35 meshed heavy wire screen and a relatively smaller frame detachably secured within the second named frame, the inner side of the last named frame being covered with close meshed, fine wire screen substantially 40 as and for the purpose herein set forth.

2. In a window, the combination of a frame adapted to fit therein, means to detachably secure said frame in said window, a layer of wire screen secured to the outside 45 of said frame and covering the opening therein; a second frame mounted in the first named frame so as to lie in the same vertical plane, means to detachably secure said frame in position, and a layer of wire screen 50 secured to the inner face of the second frame and covering the opening therein.

In testimony whereof I have hereunto set my hand.

LEE A. YEAGER.
